(57) CLAIM

I claim the ornamental design for a sports ball ashtray, substantially as shown and described.

DESCRIPTION

FIG. 1 is a top plan view of a sports ball ashtray showing my new design;

FIG. 2 is a perspective view thereof;

FIG. 3 is a top plan view of a sports ball ashtray showing a second embodiment of my new design;

FIG. 4 is a perspective view of the design of FIG. 3; and, FIG. 5 is a side elevation view of both embodiments.

The broken line showing of “Team Logo” is for illustrative purposes only and forms no part of the claimed design.
